UNITED STATES PATENT OFFICE.

WILLIAM E. LONG, OF CHICAGO, ILLINOIS, ASSIGNOR TO THE W. E. LONG CO., OF CHICAGO, ILLINOIS, A CORPORATION OF ILLINOIS.

DESIGN FOR A LABEL BLANK.

Application filed July 27, 1928. Serial No. 27,604. Term of patent 14 years.

To all whom it may concern:

Be it known that I, WILLIAM E. LONG, a citizen of the United States, residing at Chicago, in the county of Cook and State of Illinois, have invented a new, original, and ornamental Design for a Label Blank, of which the following is a specification, reference being had to the accompanying drawing, forming part thereof.

The figure is a plan view of a label blank.

I claim:

The ornamental design for a label blank, substantially as shown.

WILLIAM E. LONG.
